US00D660012S

(12) **United States Design Patent**
Enderby et al.

(10) **Patent No.:** **US D660,012 S**
(45) **Date of Patent:** **** May 22, 2012**

(54) **EMBOSSED PAPER PRODUCT**

(75) Inventors: **Sandra A Enderby**, New Franken, WI (US); **Jansen Matchett**, Moncton (CA); **David Embley**, Quispamsis (CA); **Jim Schedler**, Grand Barachois (CA)

(73) Assignee: **Irving Tissue Corporation**, Dieppe, New Brunswick (CA)

(**) Term: **14 Years**

(21) Appl. No.: **29/369,920**

(22) Filed: **Sep. 15, 2010**

(51) **LOC (9) Cl.** **05-06**

(52) **U.S. Cl.** **D5/57**

(58) **Field of Classification Search** **D5/1-4, D5/19, 47, 53, 55-58, 61, 59, 99; D6/582, D6/583, 592, 596, 616, 622; D19/5; D24/124-126; 52/660; 112/401, 416, 439; 139/383 R; 428/32, 37, 39, 66.5, 79, 85, 153, 187, 190**

See application file for complete search history.

(57) **CLAIM**

The ornamental design for an embossed paper product, as shown and described.

DESCRIPTION

The sole FIGURE is a top plan view of the embossed paper product showing our new ornamental design. The broken lines around the perimeter indicate the boundaries of the claim and form no part thereof.

1 Claim, 1 Drawing Sheet
